UNITED STATES PATENT OFFICE

ARTHUR J. CULP, OF CLANTON, ALABAMA

EXHAUST TRAP CONSTRUCTION

Application filed July 11, 1929. Serial No. 377,459.

This invention relates to an exhaust trap construction adapted for use generally in connection with the treatment of exhaust from internal combustion engines and particularly for use in connection with the exhaust trap of Letters Patent 1,673,619 issued to me on June 12, 1928 and with the apparatus disclosed in my application Serial Number 82,812, filed January 19, 1926 for an improved apparatus and method for treating exhaust of hydro-carbon engines.

It is aimed to provide a novel construction which is closed at the time the explosions occur so as to nullify the incidental sound and also to provide a construction which prevents any back pressure from entering through the exhaust pipe to the pistons or cylinders of the motor.

Another object is to provide a construction employing a novel valve which is adapted to be automatically opened through the action of the small flow of exhaust to permit the full volume of exhaust to escape and air from the atmosphere to enter and automatically close the valve construction.

The more specific objects and advantages will in part be pointed out and otherwise become apparent from a consideration of the description following taken in connection with accompanying drawings illustrating an operative embodiment.

In said drawings:—

Figure 1 is a plan view of the improved trap,

Figure 2 is an end elevation looking from the right of Figure 1,

Figure 3 is a central vertical sectional view taken on the plane of line 3—3 of Figure 1, and

Figure 4 is a cross sectional view taken on the line 4—4 of Figure 3.

Referring specifically to the drawings, 10 designates the outlet of a conventional exhaust pipe leading from an internal combustion engine. The improved trap is attached to such exhaust pipe 10 and may have a flared attaching section as at 11 partly telescoping said exhaust pipe 10 and for instance secured thereto by a clamping nut 12 threaded on section 11 and adapted

to compress binding material as at 13. Any suitable means may be employed for attaching the section 11 to the exhaust pipe 10 irrespective of differences in size or otherwise according to different makes of automobiles. 55

The exhaust gases are delivered into the section 11 and flow thence into a tubular extension 14 on a diaphragm 15 which is bolted as at 16 to flanges 17 and 18 provided on section 11 and diaphragm 15, respectively. 60 A gasket 19 is interposed between the flanges 17 and 18.

The gases are adapted to escape from the cylinder 14 through one or more ports 20 provided in its peripheral wall, which ports are normally closed by a cap valve 21 slidably telescoped over the periphery of cylinder 14 and at its free edge adapted for engagement with a gasket or packing as at 22 which is held in place by the bolts 16 and by a flange 23, also held in place by such bolts 16. 65

The flange 23 is part of a hood 24 which surrounds and is relatively large with respect to the cylinder 14 and valve 21. The end wall of cylinder 14 as designated 25 has a port 26 therethrough which is normally closed by a tapered valve 27 of plug form, carried by a stem 28. The stem 28 has an enlarged screw threaded portion 29 which is threaded in a suitable opening in the end wall of the cap valve 21 and is also engaged by nuts 30 screw threaded thereto, and one of which serves as a lock nut for the other, such nuts binding the plug 27 tightly against the inner surface of the end wall of cap valve 21. Hood 24 is open to the atmosphere at 31. 70

Fastened to the end wall 32 of hood 24, is a supplemental hood 33, by means of screws 34. The stem 28 is slidably mounted in the outer end wall of supplemental hood 33 and the wall 32 is cut away as at 34 to accommodate movement of nuts 30 and adjacent parts. An expansive coil spring 35 surrounds the 75 stem 28, bearing against the wall 33 and the nuts 30, thus urging the plug 27 normally to its seat and the cap valve 21 normally to closed position. 80

An annular flange 36 projects forwardly 100

from the wall 25 and is disposed about the opening 26 and plug 27.

The cylinder 14 serves to baffle the exhaust gases, the same moving the valve plug 27 slightly away from its seat 26 against the tension of the spring 35, thus permitting a limited quantity of the exhaust to pass between the wall 25 and end wall of the cap valve 21, the valve 21 thus being moved unitarily with the plug 27 to an extent where the valve 21 uncovers the ports 20, enabling the gas to escape through the hood 24 and into the atmosphere through the opening 31, the atmospheric pressure and spring 35 serving to instantly close the plug 27 and valve 21 after liberation of exhaust gases. It will be realized that as the explosion or explosions occur in the internal combustion engine in connection with which the invention is associated, that the ports 20 are closed by the valve 21 and that the incidental noise is practically nullified.

The valve 21 seats both against the gasket 22 and the flange 36. I find that any chattering or noise incidental to operation of valve 21 occurs mostly on the closing stroke of such valve and in view of the fact that the flange 36 is provided, such chattering or noise is muffled between the wall 25 and end wall of valve 21.

Means is provided whereby instead of automatic operation of the valve 21, the same may be opened by manual means during operation in order to test the efficiency of the device without resorting to removal of any part of the mechanism. To this end, a lever 37 is pivoted at 37^a to the supplemental hood 33 and it has a lower bifurcated end 38 straddling the stem 28 and bearing against an abutment 39 thereon. Lever 37 is maintained adjacent the hood 33 at its lower end by an expansive spring 40, engaging the same and also engaging a bracket 41 secured in place by one of the screws 34. A draw element 42 may shift the lever 37 in order to open the valve 21, such draw element being under control by means located on the dash or instrument board of the automobile or in any other convenient location.

Various changes may be resorted to provided they fall within the spirit and scope of the invention.

I claim as my invention:

1. A trap of the class described having a cylinder adapted to receive exhaust, said cylinder having an outlet port in its peripheral wall, a valve normally closing said port, said cylinder having an additional port, a portion of said valve occupying said additional port, said portion being engageable by the exhaust to displace the valve in order to uncover the first mentioned port, means providing a seat for the free edge of the valve, and a flange on said cylinder in the path of and adapted to be abutted by said valve.

2. A trap of the class described having a cylinder to receive exhaust gas, said cylinder having an outlet port in its peripheral wall and a port in its end wall, a cap valve slideable on said cylinder normally closing the discharge port, said cap valve having a plug occupying the second mentioned port, said plug being displaceable by the exhaust gases to move the valve to uncover the first mentioned port.

3. A trap of the class described having a cylinder to receive exhaust gas, said cylinder having an outlet port in its peripheral wall and a port in its end wall, a cap valve slideable on said cylinder normally closing the discharge port, said cap valve having a plug occupying the second mentioned port, said plug being displaceable by the exhaust gases to move the valve to uncover the first mentioned port, and a flange extending outwardly from said end wall and annularly around the second mentioned port and engageable by the end of the cap valve.

4. A trap of the class described having a cylinder to receive exhaust gas, said cylinder having an outlet port in its peripheral wall and a port in its end wall, a cap valve slideable on said cylinder normally closing the discharge port, said cap valve having a plug occupying the second mentioned port, said plug being displaceable by the exhaust gases to move the valve to uncover the first mentioned port, a flange extending outwardly from said end wall and annularly around the second mentioned port and engageable by the end of the cap valve, a hood about said valve and cylinder, a stem extending from said valve, means on the hood mounting said stem for sliding movement, an expansive coil spring surrounding the stem and abutting said valve and said means.

5. An exhaust trap of the class described comprising an attaching section, a diaphragm and a hood, means securing said section, diaphragm and hood together, said diaphragm having a cylinder provided with an outlet port in its peripheral wall and a port in its end wall, a cap valve slideable on said cylinder and normally closing the first mentioned port, a part of the cap valve normally closing the other port and being adapted for engagement by exhaust to move the valve to uncover the first mentioned port, and a spring against the tension of which said valve moves.

6. An exhaust trap of the class described comprising an attaching section, a diaphragm and a hood, means securing said section, diaphragm and hood together, said diaphragm having a cylinder provided with an outlet port in its peripheral wall and a port in its end wall, a cap valve slideable on said cylinder and normally closing the first mentioned port, a part of the cap valve normally closing the other port and being adapted for

engagement by exhaust to move the valve to uncover the first mentioned port, a spring against the tension of which said valve moves, a flange extending outwardly from the end wall of the cylinder and adapted to be abutted by the end wall of the cap valve, said hood being in communication with the atmosphere, and means operable manually to move said cap valve.

5 10 In testimony whereof I affix my signature.
ARTHUR J. CULP.
